(57) **CLAIM**

The ornamental design for a transitional image display for mobile phone, as shown and described.

DESCRIPTION

FIG. 1 is a front view of the first image in the sequence for a transitional image display for mobile phone;

FIG. 2 is a second image thereof;

FIG. 3 is another front view of the transitional image display for mobile phone of FIG. 1, but with alternative broken lines; and,

FIG. 4 is another front view of the transitional image display for mobile phone of FIG. 2, but with alternative broken lines.

The subject matter in this application includes a process or period in which an image changes into another image. This process or period forms no part of the claimed design.

The broken lines shown in FIGS. 1-4 are for the purpose of illustrating the present invention and form no part of the claimed design.
